CLAIM

The ornamental design for a trigger pump dispenser shroud, as shown and described.

DESCRIPTION

FIG. 1 is a perspective view of a trigger pump dispenser shroud showing my new design. The broken line environmental structure is for illustrative purposes only and forms no part of the claimed design; and, FIG. 2 is a left side elevational view.

The right side elevation is a mirror image of the left side elevation.

1 Claim, 1 Drawing Sheet

FIG. 1

FIG. 2

UNITED STATES PATENT AND TRADEMARK OFFICE
CERTIFICATE OF CORRECTION

PATENT NO. : Des. 409,915

DATED : May 18, 1999

INVENTOR(S) : Leonora M. Durliat et al

It is certified that error appears in the above-identified patent and that said Letters Patent is hereby corrected as shown below:

The title page should be deleted, and substitute therefor the attached title page.

In the Drawings:

Sheet 1 of the drawings should be deleted and substitute therefor the corrected drawing sheet as shown on the attached page.

Add the drawing sheet, consisting of Figs. 3, 4, 5 and 6, as shown on the attached page.

After the description of Fig. 2, insert:

--Fig. 3 is a top plan view;

Fig. 4 is a front elevational view;

Fig. 5 is a rear elevational view;

Fig. 6 is a bottom plan view.--

Signed and Sealed this
Seventh Day of March, 2000
